METHOD OF MAKING AXLE HOUSINGS

Rudolph H. Thoms, Cleveland, Ohio, assignor to
Midland Steel Products Company, Cleveland,
Ohio, a corporation of Ohio

Application July 15, 1931. Serial No. 550,843

14 Claims. (Cl. 29—153.1)

This invention relates to new and useful improvements in axle housings and the method of making the same.

An important object of the invention is to provide a method by which these housings can be formed from tubular stock without increasing or diminishing the original wall thickness thereof at any point, thereby producing a housing having the requisite uniform wall thickness with attendant equal distribution of uniform strength and no weak spots throughout the length of the housing.

It has been proposed to work with stock or tubing having a diameter less than that required for the enlarged end, but this necessitates enlargement of such end which is later formed into the gear housing portion, with consequent reduction in wall thickness, unless compensated for by simultaneous axial pressure upon opposite ends 20 of the tubing, or swaging prior to expansion.

In order to avoid complications resulting from the aforesaid practice, it is proposed to work with oversize stock having a diameter, so large, that the necessity for the aforesaid additional work- 25 ing is eliminated.

By the herein described method it is possible to eliminate at least one step of upsetting for each section of the housing, thereby resulting in increased production of superior housings at less 30 costs and which are not so apt to open at the seams of welded stock during their manufacture.

Other objects and advantages of the invention will become apparent during the course of the following disclosure.

35 In the accompanying drawing forming a part of the description and wherein like numerals are employed to designate like parts throughout the several views.

Figure 1 is a side elevation of a length of circular tubing from which each section of the axle housing is formed.

Figure 2 is an end elevation of the same.

Figure 3 is a side elevation of tubing after the first swaging operation, with one end thereof 45 broken away to illustrate the increased wall thickness imparted to one end of the tubing.

Figure 4 is a longitudinal section through the same section of tubing illustrating the first drawing operation.

50 Figure 5 is a similar view illustrating the second drawing operation.

Figure 6 is a side elevation of one section of the housing in a partially completed condition, and

55 Figure 7 is a plan of an axle housing practically

completed by joining two sections of tubing formed in accordance with the invention.

Referring now more specifically to the drawing, the numeral 10, designates a length of circular tubing which may be seamless or formed from strip rolled and welded longitudinally along a seam as at 11. Due to the difference in cost of the two kinds of tubing, axle housings can be formed at less cost from welded tubing and it has been found that the herein disclosed method can be carried out with less likelihood of opening the welded seam, than is the case with other methods of forming such axle housings.

Since it is preferable to carry out the process with heated stock, it may be given the herein described treatment prior to any appreciable loss of heat incidental to the formation of the stock into tubular form, thereby effecting a saving in the heating and handling of the stock. With the tubing in heated condition, one end 12, is hot swaged to reduce its diameter, increase its wall thickness and to provide an internal shoulder 13, for abutment with a shoulder 14, on a die punch 15, employed in the drawing operation. During this hot swaging operation it is important to note that the original wall thickness of the remaining portion of the tubing has not been increased or decreased and that it remains the same throughout all stages of the manufacture.

The reduced end 12 of the stock which is subsequently formed into a circumferential radial flange 16, for the attachment of a brake apron thereto, is inserted through a female die 17, after which the male die punch 15, is projected into the enlarged end of the tubing and against 90 the shoulder 13, thereof. Continued movement of the punch 15, axially of the tubing, causes elongation of the latter through the die 17, while still maintaining the original wall thickness of the tubing at all points up to the swaged end. 95 This operation is stopped short of drawing the entire length of tubing through the die thereby resulting in the formation of a shoulder 18, at a point located a distance from the enlarged end 19 thereof, sufficient to allow for enough material, of original stock diameter and wall thickness, being left for the formation of an enlarged gear housing portion 20.

After this operation the tubing is subjected to a second drawing operation through a smaller 105 die 21 with a male die punch 22. This punch is provided with a shoulder 23 for engagement with the shoulder 13 of the tubing, and when projected through the die, will further elongate the tubing and draw the same down to a smaller 110

diameter as indicated at 26 in Figure 5. It is important to note that this second drawing operation, like the first, does not in any way alter the original thickness of the walls of the tubing 5 at any point and that it remains uniform with the exception of course, of the previously swaged portion 12. Drawing the tubing through this second die, results in the formation of a second shoulder 24, in proximity to the shoulder 18, 10 both of which are later merged into a flared portion 25, as will be presently described.

The swaged end 12, is then enlarged as at 27 and upset to produce the annular thickened flange 16, to which may be secured, in any suitable manner, the brake apron heretofore referred to. The opposite enlarged end 19 of the tubing is then flattened or rather compressed to give it substantially elliptical cross section after which it is provided with a pair of diametrically disposed longitudinally extending slots 28, thereby forming the enlarged end, for a substantial portion of its length, into a pair of arms 29, arcuate in cross section. This bifurcated end is then positioned in a female die for final shaping and the arms 29 are bowed and spread apart 20 into the arcuate semi-circular formation shown by a male die section. This causes the enlarged end 19 of the tubing to be formed with the arcuated channeled gear housing portion 20 normal 30 to the longitudinal plane of the tubing and the shoulders 18 and 24 are simultaneously merged into the flaring portion 25, as indicated in Figure 7. From the foregoing it will be obvious that the original wall thickness of the stock remains 35 unchanged throughout these forming operations, thereby resulting in the production of an axle housing section which is of uniform strength throughout its length. Moreover, when welded tubing is used, the method does not cause such 40 stress upon the welded seam as would cause the same to split.

In order to complete an axle housing, two of these symmetrically formed complementary sections are placed in alignment with the arcuate 45 gear housing portions arranged with their edges 30 in abutment, which edges are welded together as at 31, thereby forming a substantially one piece axle housing. The axle housing is completed by attaching substantially circular plates, 50 not shown, to opposite sides of the complementary gear housing section 20 to form an enclosure for the differential gear unit.

It will be understood that the method is not to be limited to the sequence of steps set forth 55 in the specification or limited otherwise than recited in the appended claims. For instance, the entire drawing may be found possible in one drawing operation instead of two; or it may be expeditious to form the gear housing portions 60 while the tubing is being drawn, and again it may be desirable to form the bowed portion 27 and flange 16 after the gear housing portion is formed, instead of prior to its formation. The 65 essential factor is the maintenance of original wall thickness of the axle housing section throughout its length with the exception of its outer end at the enlargement 27 and flange 16 which latter is left thickened to impart requisite 70 strength for the attachment of the usual brake apron. When welded tubing is used instead of seamless, it is desirable but not necessary to position the slots 28 in a plane arranged at about 90° 75 from the plane of the weld so as to reduce to a minimum, any possible stress upon the welded

seam during the spreading formation of the gear housing portion.

I claim:

1. Method of forming axle housings consisting of swaging one end of tubular stock to increase its wall thickness while leaving the other end at its original size, reducing the diameter of the intermediate portion of the stock by drawing out said portion and maintaining the constant original wall thickness throughout the stock up to the thickened end; bowing outwardly the thickened 80 end and forming a flange thereon, and then forming said other end into a substantially forked portion having wall thickness no thinner than other portions of housing. 85

2. The method of forming axle housings consisting of swaging one end of tubular stock to increase its wall thickness while leaving its other end its original size, reducing the diameter of the intermediate portion of the stock while maintaining the constant original wall thickness 90 throughout the stock up to the thickened end, forming said other end into a gear housing portion, and then turning an annular radial flange on the swaged end of the stock. 95

3. The method of forming axle housings consisting of swaging one end of tubular stock to increase its wall thickness while leaving its other end at its original size, drawing out the intermediate portion of the stock to elongate and 100 reduce its diameter while maintaining the constant original wall thickness throughout the stock up to the swaged end, further drawing out said reduced portion to further elongate and reduce the primarily reduced portion while still maintaining the constant original wall thickness of the stock up to the swaged end and to form an intermediate tapered portion, upsetting the swaged 110 end of the stock to form an annular flange, and then forming the other end of the stock into a 115 gear housing portion.

4. The method of forming axle housings consisting of swaging one end of tubular stock having a longitudinally extending welded seam to increase its wall thickness while leaving its other 120 end at its original size, reducing the diameter of the intermediate portion of the stock while maintaining the constant original wall thickness throughout the stock up to the swaged end, slotting the other end of the tube in a plane normal 125 to that of the welded seam, then forming said other end in a plane parallel to that of the welded seam into a substantially forked portion, and attaching the forked portions of two such sections together. 130

5. The method of forming axle housings consisting in drawing out a portion of tubular stock while maintaining its original wall thickness and while leaving one end of the stock at its original size and wall thickness, slotting and spreading 135 said end into a gear housing portion, and then attaching the two gear housing portions of two such sections together.

6. In a method of forming an axle housing section including reducing tubular stock up to a 140 point adjacent one end to provide an enlarged end, flattening the enlarged end into substantially oval cross section, slotting said enlarged end from its free end inwardly to a point adjacent the shoulder formed by the enlarged end to provide a 145 pair of arms, and spreading said arms apart and bending them into arcuate shape.

7. In a method of forming an axle housing section including providing a tube with an enlarged end, flattening said end into substantially 150

oval shaped cross section, slotting said enlarged end from its free end inwardly for a substantial distance to provide a pair of arms, and spreading said arms apart and bending them into arcuate shape.

end, bowing outwardly the thickened end and forming a flange thereon, and forming said other end into a gear housing portion.

12. The method of forming axle housings consisting of swaging one end of tubular stock to increase its wall thickness and to provide a working shoulder while leaving its other end at its original size, drawing out a portion of the tube by engaging the shoulder to elongate and reduce the diameter of the tube while maintaining its wall thickness constant throughout the stock up to the thickened end, then further drawing out

80

said reduced portion to further elongate and reduce the primarily reduced portion while still maintaining the constant original wall thickness of the tube up to the thickened end, bowing outwardly the thickened end and forming a flange thereon, and then forming said other end into a gear housing portion.

85

13. The method of forming axle housings consisting of swaging one end of tubular stock to increase its wall thickness and to provide a working shoulder while leaving one end its original size, drawing out a portion of the stock by exerting thrust on said shoulder to elongate and reduce the diameter of the tube while maintaining its original wall thickness up to the thickened end, bowing outwardly the thickened end and forming a flange thereon, and then forming the other end having original tube diameter and thickness

90

into a substantially forked end portion having wall thickness substantially equal to the original stock.

95

14. The method of forming axle housings consisting of swaging one end of tubular stock to increase its wall thickness and to provide a working shoulder for a punch while leaving one end its original size, drawing out a portion of the stock by exerting thrust on said shoulder to elongate and reduce the diameter of the tube while maintaining substantially its original wall thickness throughout the stock up to the thickened end, then further drawing out said reduced portion to further elongate and reduce the primarily reduced portion while maintaining substantially constant original wall thickness of the stock up to the thickened end, expanding the thickened end and forming a flange thereon, and then forming the other end having original stock diameter into a substantially forked portion having wall thickness

100

105

substantially equal to the original stock.

110

15. The method of forming axle housings consisting of swaging one end of tubular stock to increase its wall thickness while leaving its other end at its original size, drawing out the intermediate portion of the tube to elongate and reduce its diameter while maintaining the wall thickness constant throughout the tube up to the thickened end, bowing outwardly the thickened end and forming a flange thereon, and forming said other end into a gear housing portion having wall thickness substantially equal to the original tube.

16. The method of forming axle housings consisting of swaging one end of tubular stock to

115

increase its wall thickness and to provide a working shoulder while leaving its other end at its original size, drawing out the intermediate portion of the tube by engaging the shoulder to

120

elongate and reduce the diameter of the tube while maintaining its original wall thickness constant throughout the stock up to the thickened end, then further drawing out said reduced portion to

125

further elongate and reduce the primarily reduced portion while maintaining substantially constant original wall thickness of the stock up to the thickened end, expanding the thickened end and forming a flange thereon, and then forming the other end having original stock diameter into a substantially forked portion having wall thickness
